UNITED STATES PATENT OFFICE

ANDREW S. VAN HALTEREN, OF EAST LANSING, MICHIGAN, ASSIGNOR TO MOTOR WHEEL CORPORATION, OF LANSING, MICHIGAN, A CORPORATION OF MICHIGAN

STEEL FELLY AND RIM CONSTRUCTION

Application filed March 12, 1928. Serial No. 260,824.

My invention relates to the construction and assembly of a metal felly about a spoke spider within a tire-carrying rim.

It is common practice to connect the wood spokes of a wheel spider by a metal felly of radially open channel formation, the channel receiving the spoke tenons in spaced apertures and supporting the rim upon one or both of the two legs of the channel and being secured thereto at one or both lines of contact.

It is difficult in manufacture to secure an exact fit of the two channel legs within the rim to provide an equal bearing of the rim on both. Due to small variations in inner rim diameter and in outer diameter of the two felly legs, it is practically impossible to be assured of a press fit between both sides of the felly and the two sides of the rim.

To obviate this difficulty, I form one leg of the felly channel of less radial height than the other and preferably incline the edge of the same to correspond to the lower rear face of the gutter portion of the Q. D. (quick detachable) rim. The other leg of the felly is of an outer diameter corresponding snugly to the inner diameter of the rim base to secure a press fit, and its edge is preferably flanged over to give an extended bearing against the inner face of the rim base whereby to afford an area for welding, riveting or otherwise securing to the rim against lateral displacement. The legs of the felly are spaced apart a sufficient distance so that they can be deformed slightly to place the front leg under lateral stress against the gutter portion of the rim when the felly is assembled with the rim.

By this construction it is only necessary to size the rear leg of the felly accurately, the fit of the front leg within and against the gutter at the front edge of the rim being assured by forcing the rim and felly laterally into pressure contact with sufficient force to slightly deform the legs of the felly and maintaining the front leg under stress by permanently attaching the rim and rear leg as by riveting or welding. The front leg being thus maintained under lateral pressure against the gutter of the rim, due to the elasticity of the metal in the felly, a snug fit is

secured, thereby eliminating relative movement between the front leg and the rim which would otherwise result in noise and squeaks.

In order that the invention may be more readily understood from the following description, a preferred and modified embodiments of the invention are set forth by way of illustration in the accompanying drawing; it being understood that other modifications are contemplated as within the scope of the 55 mechanic following upon a disclosure of the invention herein. In the drawings:

Fig. 1 is an elevation of a wood spoke wheel embodying the invention;

Fig. 2 is a radial section of a wheel corresponding to the line 2—2 of Fig. 1;

Fig. 3 is a similar view taken on a line corresponding to line 3—3 of the drawing and illustrating a modified connection between the rear leg of the felly and the rim;

Fig. 4 is a detail of the felly and rim assembly illustrating upon a larger scale one form of bearing connection between the front leg of the felly and the rim; and

Fig. 5 is a view similar to Fig. 4 illustrating a modified bearing connection between the front felly leg and the gutter.

Referring to the drawings, the spokes 11 having tenons 11^a are secured in assembled 80 spider relation at the hub portion by the plates 12 and 12^a and the ferrule rivets 13.

The rim here illustrated is of the well known Q. D. type and comprises the rim base 14, the tire-retaining flange 15 and the front gutter or rib 16 for receiving the usual 85 split ring, not shown.

The metal felly, of outwardly open channel formation, comprises a drop base 17, apertured to receive the spoke tenons, a rear leg 18 flanged over at 19 and a front leg 20 of less radial height than the rear leg 18 and provided with an inclined face to fit the rear face of the gutter 16, either by beveling as indicated at 21 in Figs. 2, 3 and 4, or inwardly turned as indicated at 22 in Fig. 5. The 90 valve stem opening is indicated at 17^a.

The assembly of the felly with the spider is accomplished by seating the spoke tenons 11^a in the apertures provided in the felly and clamping the inner ends of the spokes in the 100

hub zone between plates 12 and 12^a in the usual manner. The assembly of the rim with the wheel spider and encompassing felly is attained by forcing the rim laterally towards the rear upon the felly or the felly laterally towards the front within the rim. In practice it is found desirable to apply sufficient pressure to the felly to spring the ends of the legs 18 and 20 towards each other approximately one-sixteenth of an inch and fasten the flange 19 to the rim while the felly is under pressure, thus utilizing the elasticity of the metal in the felly to maintain the leg 20 in pressure contact with the inclined rear face of the gutter 16. The flange 19 of the rear leg 18 is secured to the rim by spot or line welding as indicated at 23 in Fig. 2, or by indenting into interlocked relation as indicated at 24 in Fig. 3, or by riveting as indicated at 25 in Figs. 4 and 5, either method of attachment providing a metal interlock of the felly and rim.

It is obvious that any inwardly extending flange or rib carried by the rim in front of its median line may be utilized as the equivalent of the gutter 16 to provide an incline bearing for the front felly leg.

It will thus be understood that I have devised a felly construction and rim assembly wherein accuracy of manufacture as to the radial dimensions of the front edges of the felly and rim is rendered of no consequence inasmuch as an exact fit is attained due to the legs of the felly being slightly deformed so that the elasticity of the metal forces the front leg against the inclined rear face of the gutter or equivalent flange or rib. The requirement for manufacturing accuracy of dimensions applies only to the rear leg of the felly in relation to the rim diameter at the rear, any slight inaccuracies at this point being compensated by the permanent attachment effected by the welding of Fig. 2, the indenting of Fig. 3 and the riveting of Figs. 4 and 5, whereby any lateral shifting of the front leg of the felly out of pressure contact with the gutter 16 is precluded. The steps of manufacture and of assembly are greatly simplified and cheapened by this construction.

I claim:

1. In a wheel assembly, a spoke spider, an outwardly opening channel felly member encompassing the spider and accommodating the spoke tenons within apertures of its base, a tire-carrying rim having along its front edge an inwardly extending rib, the rear leg of the felly adapted to fit closely within the rim and the front leg bearing against and in stressed relationship with the rib, the rear leg of the felly being permanently secured to the rim.

2. In a wheel assembly, a spider, an outwardly opening channel felly member encompassing the spider, a tire-carrying rim

having along its front edge an inwardly extending rib, the rear leg of the felly adapted to fit closely within the rim and the front leg bearing laterally against and in pressure contact with the rib, the rear leg of the felly being permanently secured to the rim. 70

3. In a wheel assembly, a wheel body, an outwardly opening channel felly member encompassing and secured to the wheel body, a tire-carrying rim having along its front edge 75 an inwardly extending rib, the rear leg of the felly adapted to fit closely within the rim and the front leg bearing against and in stressed relationship with the rib, the rear leg of the felly being permanently secured to the rim. 80

4. In a wheel assembly, a metallic felly, and a rim having an inwardly extending rib with an inclined face, the felly comprising a channel member having one leg permanently 85 secured to the rim base and the other leg arranged to bear against the inclined face of the rib and in stressed relation thereto.

5. In a wheel assembly, a wheel body, a metal felly, and a rim having an inwardly 90 extending rib, the felly comprising a channel member encompassing and secured to the wheel body and having legs of unequal radial height, one leg fitting closely within and permanently attached to the rim base and 95 the other leg having a bearing against the rib at an inclination to the wheel plane, said bearing being under pressure and maintained by the permanent attachment of the other leg to the rim. 100

In testimony whereof I have hereunto subscribed my name.

ANDREW S. VAN HALTEREN.
